CLAIM

The ornamental design for an outdoor grill, as shown and described.

DESCRIPTION

FIG. 1 is a front, right perspective view of our new design for an outdoor grill.

FIG. 2 is a front view of the outdoor grill shown in FIG. 1.

FIG. 3 is a back side view of the outdoor grill shown in FIG. 1.

FIG. 4 is a left side view of the outdoor grill shown in FIG. 1.

FIG. 5 is a right side view of the outdoor grill shown in FIG. 1.

FIG. 6 is a top view of the outdoor grill shown in FIG. 1; and,

FIG. 7 is a bottom view of the outdoor grill shown in FIG. 1.

The broken lines illustrate portions of the outdoor grill and form no part of the claimed design.

1 Claim, 7 Drawing Sheets
